TROPHY BASE

Thomas F. Merle, Lincolnwood, Ill.

Application March 18, 1957, Serial No. 45,315

Term of patent 14 years

(Cl. D29—23)

Fig. 1 is a front elevational view of a trophy base showing my new design;

Fig. 2 is a side elevational view; and
Fig. 3 is a top plan view thereof.

I claim:

The ornamental design for a trophy base, as shown.
